UNITED STATES PATENT OFFICE

LEWIS R. DORRIS, OF PENSACOLA, FLORIDA

PROPELLER FOR SWIMMERS

Application filed January 5, 1931. Serial No. 506,513.

This invention relates to propellers for swimmers; and has special reference to devices to be attached to the legs of the swimmers so as to open and move in one direction and thus aid in propelling the swimmer forwardly through the water, and close when drawn forwardly through the water so as to offer little or no resistance to the forward movement of the swimmer.

10 An object of the invention is to provide a device of the type and character mentioned that may be easily and quickly attached to and removed from the legs of the swimmer and that will open and close automatically and as an incident to the natural movement of the legs in swimming so as to accelerate and facilitate the movements of the swimmer through the water.

Other objects will appear from the following description, reference being made to the accompanying drawings, in which—

Fig. 1 is a perspective view of the device in its open adjustment.

Fig. 2 is a similar view of the device closed.

25 Fig. 3 is an enlarged perspective view of the device detached from the wearer.

The device comprises a band 1, preferably characterized by a certain degree of elasticity so as to fit closely around the leg of the wearer 30 for which the device is constructed but which will not yield or expand so easily that it will permit water to pass between the band and the leg to such an extent as to destroy or seriously interfere with the function of the device. This band may be an endless band, as shown, or may be otherwise constructed.

One end of a section 2 is attached to the band 1 and the opposite end of said section 2 is free. This section 2 may be of canvas or other appropriate textile material, or it may be of canvas or of some textile material impregnated with rubber or similar substance so as to be characterized by a substantially non-absorbent quality. The end 45 of the section 2 that is attached to the band 1 is gathered and the other end of said section 2 is free to expand so as to form an approximately conical shape, as shown in Fig. 1 of the drawings. The section 2 is provided with fold lines 3 due to the gathers

formed at the end of said section 2 that is attached to the band 1. These fold lines facilitate the opening and closing of the section 2, so that when pushed against the water by the wearer in the operation of swimming, 55 said section 2 will open to substantially umbrella-like form and thus provide a propeller to act as an aid in swimming. When the legs are drawn forwardly, the device will fold along the lines 3 to approximately the shape 60 shown in Fig. 2 and when pushed rearwardly will open as shown in Fig. 1.

A strap 4 has its ends attached to the band 1 and is adapted to be engaged under the heel portion of the foot of the wearer, as 65 shown, in order to prevent the device from slipping.

This device may be manufactured and sold at comparatively low cost and is sufficiently 70 durable for the purposes for which it is intended. It will facilitate and accelerate the action of swimming and constitutes no inconvenience to the wearer.

I claim:

A device of the character described comprising an elastic band adapted to encircle the leg of the wearer above the ankle, a ring of non-elastic pliable material of larger diameter than said band having one end gathered and attached to said band throughout the 80 circumference of the band and ring and having the other end detached and having fold lines extending from said band to the opposite end of said ring of pliable material, the pliability of said ring being unrestricted and unrestrained throughout its length and circumference, and a strap having its ends attached to said band within said ring and arranged to extend under the foot of the 85 wearer.

LEWIS R. DORRIS.
